UNITED STATES PATENT OFFICE

DAVID C. PRINCE, OF SCHENECTADY, NEW YORK, ASSIGNOR TO GENERAL ELECTRIC COMPANY, A CORPORATION OF NEW YORK

VACUUM CIRCUIT INTERRUPTING APPARATUS

Application filed July 14, 1930. Serial No. 467,717.

My invention relates to vacuum circuit interrupting apparatus.

The interruption of a high voltage circuit by a vacuum device, as a fuse or switch, comprising a highly evacuated envelope within which the interrupter terminals or electrodes are sealed, depends not only upon the degree of vacuum within the envelope but also upon the possibility of preventing voltage breakdown of the gap between the terminals of electrodes immediately upon opening of the circuit. That is, the dielectric strength of the vacuum gap must hold back the rapidly increasing voltage, or recovery voltage, across the circuit interrupter terminals upon interruption of the circuit. Otherwise, the interruption is of but short duration and arcing is reestablished. The critical value of the breakdown voltage for a given gap is uncertain and the dielectric strength of the gap may fail under varying conditions. In vacuum circuit interrupting devices heretofore developed, the terminals of the interrupting devices, when in the open circuit position, are separated by the vacuum gap itself so that a voltage breakdown may occur directly between the electrodes to re-establish arcing.

It is a principal object of my invention to provide an improved vacuum or low pressure alternating current circuit interrupter which shall have means for reducing the probability of voltage breakdown between the electrodes of the interrupter when separated by a gap in vacuum.

In accordance with my invention a vacuum circuit interrupter is provided with one or more conducting grids or barriers arranged so as to be interposed in the gap between the electrodes of the interrupter and free to assume any potential. In other words, the grids have no definite or fixed potential in the open circuit position of the interrupter and may therefore be termed floating with respect to the electrodes. I have found that in evacuated or low pressure envelopes having floating grids interposed in the gap between the electrodes, the breakdown voltage between the electrodes is appreciably higher than in the case of grids

having a fixed potential or in the case of a clear gap with no grids. The explanation for this phenomena would appear to be in the characteristic difference between a voltage breakdown in vacuum, or a gas, as mercury vapor at low pressure, and a breakdown in air or other gas particularly subject to ionization. When a voltage breakdown occurs between electrodes separated within a highly evacuated envelope for example, the breakdown may be but momentary since there is no continued ionization in the path of the breakdown. In other words, the vacuum gap recovers its full dielectric strength practically instantaneously. In the case of air or a like gas, on the other hand, the breakdown generally is permanent or of appreciable duration due to the continued ionization of the air. The ionized gas makes a good conductor between the electrodes so that the gap may not recover its full dielectric strength during the reversal of the voltage impressed across the same. Accordingly, in the event of a momentary breakdown between a grid and one anode, the voltage may collapse between the grid and that anode but the breakdown will not extend to the other anode due to the fact that the double voltage does not remain on the other gap for a sufficient length of time. The probability of a complete breakdown is thus very greatly reduced.

My invention will be more fully set forth in the following description referring to the accompanying drawing, and the features of novelty which characterise my invention will be pointed out with particularity in the claims annexed to and forming a part of this specification.

Referring to the drawing, Fig. 1 is a view, partly in section, illustrating a vacuum fuse embodying my invention and Fig. 2 is a view, partly in section, of a vacuum switch likewise embodying my invention.

The vacuum fuse illustrated in Fig. 1 may be of conventional type and comprises in the present instance a highly evacuated envelope 1 through which the electrodes or terminals 2 and 3 are sealed. The fuse envelope and electrodes are freed of occluded

gases in any suitable manner so that the vacuum, which is as high as may be practically obtained, shall not be impaired by gasses formed during circuit interruption.

- 5 The electrodes 2 and 3 which are composed of material particularly suited for the interruption of alternating current or direct current, such as for example tungsten for direct current and a metal having a low melting point as nickel or copper for alternating current, are interconnected within the evacuated envelope by a fusible element 4 and are electrically connected exteriorly of the envelope to the terminal caps 5 and 6 secured in a well known manner to the envelope 1. The electrodes may likewise be provided with shields 2' and 3', respectively, disposed adjacent the sealing-in portions of the electrodes for protecting the same from injurious effects of arcing.

For the purpose of increasing the effective breakdown voltage between the electrodes 2 and 3 when the fusible element 4 has been vaporized or otherwise removed from the gap between the terminals there is provided means comprising the grids 7 and 8 arranged in the gap between the electrodes and spaced preferably equal distances with respect to each other and the electrodes.

25 The grids 7 and 8 are in the present instance constructed of wire mesh in the form of a disc although it shall be understood that the grids may comprise solid metallic discs as well.

- 30 When the fusible element 4 is ruptured or vaporized due to excess current, the arcing between the electrodes, if continued, must form a plurality of arcs in series between the electrodes and grids. That is, the voltage breakdown of the gaps in series must be concurrent for the arc to persist. For the purpose of removing the conducting fusible element 4 from the gap in the event that it is not completely vaporized, suitable means 40 as springs under tension (not shown) may be connected to the fusible element so as to withdraw the unvaporized portions from the grids and from the gap, and to this end the fusible element 4 extends freely through the central portions of the grids and is not fixed thereto. The full voltage is, therefore, practically immediately, depending on the rate of voltage rise, impressed across the terminals 2 and 3 and the fuse, tending 45 to cause voltage breakdown of the gap and consequent re-establishing of the current. However, due to the fact that a momentary voltage breakdown between one electrode and a grid adjacent the same may occur 50 without necessarily causing breakdown of the other gap or gaps, the grids 7 and 8 are effective to increase the apparent dielectric strength of the space between the electrodes so that after the first current zero a higher 55 breakdown voltage would be required to

break down this space than is usually the case. Or, in other words, there is less probability of voltage breakdown between the electrodes for a given terminal or applied voltage.

70 In the embodiment of my invention illustrated in Fig. 2 a vacuum switch, comprising a highly evacuated envelope 9 and relatively movable electrodes 10 and 11 having contact portions 12 and 13 at the adjacent ends thereof, is provided with a grid 14 of the character above described disposed in the envelope 9 between the contact portions 12 and 13 of the electrodes. As in the previous instance, the switch envelope and parts 80 thereof are freed of occluded gases and the electrodes are composed of material most suitable for current interruption. The electrodes 10 and 11 are sealed at opposite ends of the switch through the flexible metallic bellows 16 and 17 so that the electrodes may be moved longitudinally in opposite directions away from the grid 14 during the circuit interrupting operation. The grid 14 is in the present instance provided with a 90 conducting portion 15 disposed centrally thereof which is engaged at opposite sides by the contact portions 12 and 13 when the switch is in the closed circuit position illustrated in Fig. 2. The circuit opening operation is effected by simultaneously moving the contacts 12 and 13 in opposite directions away from the grid 14 so as to form two gaps in series between the contacts. The current is more readily interrupted at the first current zero with the floating grid interposed in the gap between the contacts by reason of the fact that there are two gaps in series with no ready communication for ionization established in one gap to the other 95 gap.

100 It shall be understood, of course, that my invention is not limited to any particular number of grids or barriers in the gap between the electrodes and that the character and number of grids may be chosen in accordance with the particular operating requirements involved.

110 It shall be further understood that my invention is not limited to specific details of construction and arrangement thereof herein illustrated, and that changes and modifications may occur to one skilled in the art without departing from the spirit of my invention.

115 What I claim as new and desire to secure by Letters Patent of the United States, is:

1. A vacuum alternating current circuit interrupter comprising a highly evacuated envelope, electrodes extending within and sealed with respect to said envelope, conducting means interconnecting said electrodes in the closed circuit position of the interrupter, said electrodes being separated 125 by a gap in vacuum in the open circuit posi- 130

tion of the interrupter, and a grid of conducting material having no fixed potential interposed in said gap between the electrodes and spaced with respect to the electrodes, said grid positioned in said vacuum gap so that it may assume an individual potential upon reversal of voltage across said electrode.

2. A vacuum alternating current fuse
 10 comprising a highly evacuated envelope, electrodes extending through and sealed with respect to said envelope, a fusible element interconnecting said electrodes within the envelope, and a conducting grid
 15 interposed between the portions of said electrodes to which the fusible element is connected and arranged so that upon blowing of said fusible element a vacuum gap is created between each of said electrodes
 20 and said grid.

3. A vacuum, alternating current switch comprising a highly evacuated envelope,

electrodes, sealed and mounted for relative movement with respect to said envelope, said electrodes having contacts movable within said envelope, and a conducting grid interposed between said contacts so as to form therewith two gaps in series between said contacts during opening movement of the switch.

4. A vacuum switch comprising a highly evacuated envelope, electrodes sealed and mounted for relative movement with respect to said envelope, said electrodes having contacts movable within said envelope, a conducting portion disposed between and interconnecting said contacts in the closed circuit position, and a conducting grid mounted in said envelope and connected to and supporting said conducting portion, said grid being separated from each of said contacts by a vacuum gap in the open circuit position of said switch.
